UNITED STATES PATENT OFFICE.

GUSTAV OBERSTEBRINK, OF ALLENSTOWN, NEW HAMPSHIRE.

DESIGN FOR DRESS-TRIMMING BRAID.

Application filed December 17, 1924. Serial No. 11,728. Term of patent 3½ years.

To all whom it may concern:

Be it known that I, GUSTAV OBERSTE-
BRINK, a citizen of the United States, resid-
ing at the village of Suncook, in the town
of Allenstown, in the county of Merrimack
and State of New Hampshire, have invented
a new, original, and ornamental Design for
Dress-Trimming Braid, of which the fol-
lowing is a specification, reference being had

to the accompanying drawing, forming a
part thereof.

The figure is a plan view of the dress
trimming braid, showing my new design.

I claim:

The ornamental design for dress trim-
ming braid, as shown.

GUSTAV OBERSTEBRINK.
